UNITED STATES PATENT OFFICE.

JOHN RANDOLPH SEES, OF NEW YORK, N. Y., ASSIGNOR TO WILLIAM F. WEAVER, OF PHILADELPHIA, PENNSYLVANIA.

IMPROVEMENT IN FEED-WATER HEATERS FOR LOCOMOTIVES.

Specification forming part of Letters Patent No. 42,539, dated April 26, 1864.

To all whom it may concern:

Be it known that I, JOHN RANDOLPH SEES, of the city of New York, in the State of New York, have invented a certain new and useful Improvement in Feed-Water Heaters for Locomotive and other boilers; and I do hereby declare the following to be a full, clear, and exact description thereof, reference being had to the accompanying drawing, and to the letters and marks thereon.

The drawing forming part of this specification shows by elevation a view of the interior of the smoke-box of a locomotive-boiler with a feed-water heater therein, which heater consists of a coil of pipe, *a*, the lower end thereof being in communication with the valve-chamber *b*, through which the feed-water passes by a pipe, *c*, and the upper end of said coil being in communication with the water-space of the boiler by a pipe, *d*. The valve-chamber is also shown as being in communication with the water-space of the boiler by a circulating pipe, *e*. The exhaust-pipes *f* are shown in position for discharging the exhaust-steam up within the coil of the heater. Around the coil at three different points are shown annular bands, the same being horizontal sections of cones. These bands, *g*, may be at such points of the coil and in such relation to the fire-tubes of the boiler as may be deemed best for the purposes designed for any special boiler in which they may be used, and the num-

ber may be greater or less than here shown and named. It will readily be seen that by the use of these bands the heated products of combustion in coming out of the tubes will be interrupted in their ascent, and hence more of the heat be given off to the coil. It will also be seen that by placing these bands in line with certain portions of the tubes the draft through such tubes will be to some considerable extent controlled and regulated, and thus the distribution of the heated products through the upper, or the lower, or the middle portion of the tubes be made more regular and uniform.

The annular bands *g* may be permanently affixed to the pipe of the heater by any suitable means; or they may be detachable or removable, so that they may readily be placed in a higher or lower position or nearer to or more remote from each other, for which purpose any appropriate devices may be used.

What I claim as new, and desire to secure by Letters Patent, is—

Surrounding portions of the feed-water heater with the annular bands, as and for the purposes herein set forth.

This specification signed this 30th day of September, 1863.

JOHN RANDOLPH SEES.
